Primary Examiner — Darlington Ly

(57) **CLAIM**

The ornamental design for an electric tricycle, as shown and described.

DESCRIPTION

FIG. 1 is a top, front and right side perspective view of an electric tricycle embodying my new design;

FIG. 2 is a bottom, rear and left side perspective view thereof;

FIG. 3 is a right side elevation view thereof;

FIG. 4 is a left side elevation view thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is an enlarged and partial perspective view of portion 9 in FIG. 1;

FIG. 10 is an enlarged and partial perspective view of portion 10 in FIG. 1;

FIG. 11 is an enlarged and partial perspective view of portion 11 in FIG. 1;

FIG. 12 is an enlarged and partial perspective view of portion 12 in FIG. 2;

FIG. 13 is an enlarged and partial perspective view of portion 13 in FIG. 2; and,

FIG. 14 is an enlarged and partial perspective view of portion 14 in FIG. 2.

The broken lines in the figures illustrate portions of the electric tricycle that form no part of the claimed design. The dash-dot broken lines in the drawings are for annotative purposes and are provided to indicate the areas of enlargements. They do not represent actual structure.

1 Claim, 14 Drawing Sheets
